UNITED STATES PATENT OFFICE.

GEORGE L. COLLORD, OF SHARPSVILLE, PENNSYLVANIA, ASSIGNOR TO BLAST FURNACE APPLIANCES COMPANY, OF CLEVELAND, OHIO, A CORPORATION OF OHIO.

BLAST-FURNACE.

1,234,630.

Specification of Letters Patent.

Patented July 24, 1917.

Application filed March 6, 1917. Serial No. 152,918.

To all whom it may concern:

Be it known that I, GEORGE L. COLLORD, residing at Sharpsville, in the county of Mercer, and State of Pennsylvania, a citizen 5 of the United States, have invented or discovered certain new and useful Improvements in Blast-Furnaces, of which improvements the following is a specification.

My invention relates to blast furnace tops 10 and to other apparatus of the same general nature. The object particularly in view is the even distribution within the furnace itself of the material fed in at the mouth.

This matter of the distribution of the 15 charged-in material has engaged the attention of the designers of blast furnaces to a very considerable extent. The material as it is spilled from one side of the skip, in ordinary blast-furnace operation, inevitably undergoes a certain segregation: the larger 20 pieces fly farther, while the finer pieces fall more nearly vertically from the rim of the skip. This tendency to inequality in distribution is augmented and the problem 25 complicated by other factors: there may be irregularity in the run of material, due to preliminary handling of it; there may be irregularity due to the manner of loading the skip; the material has a tendency to bank up 30 on that rim of the skip over which it is spilled; and the bell-rod in the furnace mouth extending as it does through the path of the spilled-in material, constitutes another disturbing circumstance. These conditions, 35 with their consequent disturbing effects, require to be dealt with, in order that the supply of material to the furnace shall be uniform and uniformly distributed.

My invention, directed as it is to solving 40 the problem which I have indicated, takes its place among others as a simple solution, convenient in matters of structure and arrangement, readily applicable to furnaces already built, positive in its action, effective, and durable; furthermore, it is automatic in action; 45 and, accordingly, in its use, chances of error by operators are eliminated.

The invention is illustrated in the accompanying drawings. Figure 1 is a view in 50 side elevation of the upper part of a blast furnace, and of the skip-hoist therefor, to which my invention is applied; Fig. 2 is a like view, but to larger scale, of the furnace top and the immediately associated parts;

Fig. 3 is a third view in side elevation of the 55 furnace top and associated parts. It is drawn to a scale intermediate between that of Fig. 1 and that of Fig. 2; the point of view is remote 90° from that of Figs. 1 and 2 and, for the sake of clearness, certain 60 mechanical parts shown in Figs. 1 and 2 are omitted from Fig. 3. Fig. 4 is a schematic view of the driving mechanism, shown in elevation; Figs. 5-11 illustrate details of the driving mechanism; Fig. 12 is a fragmentary view partly in elevation partly in section on the line XII-XII Fig. 4.

1 is the furnace. In the mouth of the furnace is arranged the hopper 2, called the main hopper. The main hopper is provided 70 with the downwardly opening bell 3, called the large bell. A casing 4 incloses the main hopper above, and through this casing, in axial alinement with the main hopper, is an opening in which is arranged the distributor 75 5.

6 is the skip-hoist, and 7 a skip on the hoist. In Fig. 1 the skip is shown in full lines at the bottom of the hoist, in position to be loaded, and in dotted lines at the top 80 of the hoist (cf. Fig. 2), in position to spill its load into the distributor. 8 is the rope by which the skip is hung and raised, 9 the sheave over which the rope passes, and 10 the drum of the hoisting engine. These features are common in blast-furnace designing.

The large bell 3 is hung from a cross-head 11 (Fig. 3) and is raised and lowered by the swinging of beams 12, and the swinging of these is effected by the motor element 90 (here shown to be a steam cylinder 13 Fig. 1), whose moving member is connected to a cross-head 14, this cross-head in turn being connected to beams 12. The large bell and the apparatus for raising and lowering it 95 will not further concern us.

The distributor 5 is best shown in Figs. 2 and 3. It is a cylindrical receptacle, open above, and provided with a sloping hopper-like bottom 15 with a central opening. The 100 opening in the bottom of the distributor is controlled by the distributing bell 16.

As has been said, the distributor is arranged in the opening in the casing 4 of the main hopper. It is vertically movable 105 (within a range not ordinarily great), and is rotary on its axis, to a degree hereinafter indicated. It is supported, when the dis-

tributing bell 16 is raised, by resting on the bell itself, and, when the bell is lowered, it is supported on the rim of the opening in casing 4.

5 The bell 16 is secured on the distributer shaft 17. This shaft extends upward centrally through the distributer itself and is journaled for rotation in cross-head 18. Cross-head 18 is carried on beams 19 pivoted in the frame of the structure and 10 swung, to raise and lower bell 16, by the motor element here shown to be a steam cylinder 20, called the bell cylinder. A cage, consisting essentially of the vertical bars 212, 15 mounted on casing 4, holds the distributer when raised on bell 16 from swinging laterally, out of alinement.

Rotation is imparted to distributer shaft 17, bell 16, and distributer 5 when carried 20 by the bell, by means of a wheel 21, suitably mounted for rotation in the frame of the structure, to which the shaft 17 (preferably by an enlargement 22) is splined. The wheel 21 is rotated by the shifting of 25 a piston in a cylinder 23, called the distributer cylinder, conveniently situated, and here shown to be carried on the under side of the skip-hoist frame-work. A rope 24 with opposite ends secured to the ends of 30 the piston rod of cylinder 23 (the rod extends through both cylinder heads), and traveling upon suitably disposed sheaves 25, 26, 27, encircles wheel 21, and to the rim of the wheel it is at one point secured. A 35 turn-buckle 28 may be provided for the purpose of keeping the rope 24 taut. The distributer cylinder is so proportioned and the effective stroke of its piston is of such predetermined length that a full stroke will 40 have the effect of turning the distributer through a predetermined fraction of a complete rotation; preferably, and in accord with my invention in its more specific feature, this predetermined fraction is exactly 45 one third of a complete rotation: that is to say, the distributer turns in response to each complete traverse of the piston in cylinder 23 through an angular swing of 120° . The value of such a limited and incomplete rotation will presently be made apparent.

It will be understood that, when the shaft 17 is raised and the distributer hangs suspended from beams 19, the distributer may, by the instrumentalities which have now 55 been described, be rotated alternately in one direction or in the other; and it will further be understood that, as beams 19 are swung from the position last indicated, their inner ends (the left-hand ends, Fig. 1) descending, the distributer 5 will first be seated on the rim of casing 4, and, as the beams swing farther, the distributing bell 16, upon which the distributer had up to that point in the operation rested, will now move away from 60 the opening in the bottom of the distributer,

to the position indicated in Figs. 1-3 of the drawings. When the distributing bell is in this position the distributer is open through its hopper-like bottom, to discharge material to the main hopper 2. Thereafter the swinging of the beams 19 in opposite direction will first effect the closing of the hopper-like bottom of distributer 5, and will then lift distributer 5 from the rim of casing 4 and hold it suspended.

It remains to describe the means employed for correlating the several mechanisms and for bringing them into successive automatic operation.

Referring to Fig. 4, the operative relationships of the motor elements already mentioned is shown in a schematic manner. The bell cylinder, by which the distributer is raised and lowered, and when lowered opened to discharge, is indicated at 20; and the distributing cylinder, by which the distributer when raised is rotated, is indicated at 23. 30 is a steam line (other equivalent fluid pressure may, of course, be employed) and this steam line leads through two branches to two valve chests, 31 and 32. In valve-chest 31 is a valve which, turning from one to the other of the two positions indicated in Fig. 4 by the lines $a-a$ and $b-b$, reverses the steam supply to and escape from cylinder 20, so that the piston within the cylinder 20 is driven in alternate strokes from one end of the cylinder to the other. (This cylinder is, as has been said, the bell cylinder, and, by the reciprocation of the piston within it, the distributing bell 16 is lowered and raised again, to alternately empty the distributer and to raise and carry the distributer in position to receive a charge.) In valve-chest 32 is a valve capable of being shifted from one to another of three successive positions, diagrammatically indicated in Fig. 4 by the lines $a-a$, $b-b$, and $n-n$. When the valve is in position $a-a$ the steam supply and exhaust passages are so arranged that the piston is driven to one end of the cylinder; when the valve is in position $b-b$ the piston is driven to the opposite end; and when the valve is in the position $n-n$ there is no reversal, but the piston remains at that end of the piston chamber to which it had previously been driven. (Cylinder 23 is, as has been said, the motor cylinder for rotating the distributer; and the effective stroke of the piston within it is such that, by the shifting of the piston, the distributer—in raised position—is turned first to the right and then to the left through an angular swing of 120° . When, however, the valve 115 comes to neutral position, there is no turning of the distributer.)

Mechanism is provided to give the following sequence in operation:

(1) The skip rises and spills into the dis-

tributer, which at the time is sustained on the distributing bell in elevated position;

(2) The distributer turns through an angular swing of 120° to the right:

5 (3) The distributing bell descends and effects the discharge of the distributer:

(4) The distributing bell rises again and, raising the distributer from its seat on the rim of casing 4, sustains it in the initial 10 elevated position:

(5) Step 1 above is repeated;

(6) The distributer turns through an angular swing of 120° to the left;

(7) Step 3 above is repeated;

15 (8) Step 4 above is repeated;

(9) Step 1 above is repeated. This time there is no turning of the distributer, but the descent of the bell ensues and steps 3 and 4 above follow upon step 1. Thereafter 20 the apparatus comes again to initial position, whereupon the sequence of operation here detailed is repeated.

All of these movements, taking place in regular and recurrent succession, are conveniently accomplished by the automatic apparatus now to be described (or its equivalent), the operation being synchronized to and controlled in its operation by the recurrent rise of the skip to the furnace top.

30 Turning to Fig. 1 it will be seen that the skip 7 in its travel on the hoist 6 is counterweighted, by weight 33. When the skip is at the bottom of the hoist (as shown in full lines) weight 33 hangs at its highest point; 35 as the skip rises the weight descends, until, when the skip reaches the spilling position above the distributer in the furnace top (shown in dotted lines, Fig. 1), weight 33 has reached its lowest point (shown also in 40 dotted lines). Suitable well known intermediate instrumentalities (not shown) may of course be employed, if desired, so that the range of movement of weight 33 shall be but a fraction of the range of movement of 45 the skip on the hoist. (In case the invention is to be applied to a furnace already built, if no counterweight already exists, such an one may easily be provided.)

At a suitable place in the structure a 50 horizontally extending shaft 34 is mounted for rotation; mechanism is provided for turning shaft 34, step by step, in a predetermined succession of partial and unequal rotations, in response to the successive descents of weight 33. These unequal partial 55 turnings of shaft 34 (together with the synchronized movement of mechanism presently to be described) effect the orderly sequence of operative steps enumerated above.

60 At the lower end of the path in which the hanging weight 33 descends is arranged a slide 35, and adjacent shaft 34 is hung a weight 36, and slide 35 and weight 36 are connected, as by the rope indicated in Fig.

the lower end of its range of movement it engages and carries with it the slide 35, and in so doing raises weight 36. These two weights 33 and 36 are shown in Fig. 1, in full lines at one end of the range of movement, and in dotted lines at the other end.

70 Turning now to Figs. 5 and 7, and comparing them with Fig. 1, shaft 34 will be seen to be provided with two toothed wheels 37 and 38, keyed to it and spaced apart one

75 from the other; and weight 36 will be seen to be provided with a finger 39 which extends between the wheels 37 and 38 and which as weight 36 moves up and down reciprocates vertically, and in a tangential direction with respect to the two wheels. The

80 wheels are toothed, one with three teeth, extending at three of four quadrant points about the periphery, the other with a single tooth. And the two wheels are so placed

85 relatively one to another that the single tooth on the latter extends at that point in the periphery of the structure as a whole where the former wheel is blank, having no tooth. This is well illustrated in Fig. 7.

90 The finger 39 is provided on opposite sides with pins 40 and 41, the pin 40 extending to engage the teeth of the three-toothed wheel 37, the pin 41 extending to engage the tooth on wheel 38 (when in proper position), and the pin 41 being arranged at proper distance rearward of pin 40 to effect the end now to be described.

95 The parts being in the position indicated in Fig. 7, it is to be understood that weight 36 is raised. Weight 36, carrying finger 39, descends when the skip after spilling its load begins to descend the hoist, and rises again when the skip bearing a new load up the hoist approaches spilling position. With 100 each such descent and rise of the skip finger 39 moves longitudinally (*i. e.* vertically) from the full line position shown in Fig. 7 to the dotted line position and back again. When now (Fig. 7) finger 39 descends next 105 time, pin 40, engaging the properly positioned tooth on wheel 37, will turn shaft 34 through a quarter rotation (90°) and will then rise again. With the next descent of

110 finger 39, pin 40 will engage a tooth on wheel 37 and turn the shaft 34 through a quarter rotation, as before, and then, the single tooth on wheel 38 coming to proper position and pin 41 engaging that tooth, the continued descent of finger 39 will effect 115 the further turning of shaft 34 through a second quarter rotation. So that, on this second reciprocation of finger 39, the shaft 34 is turned through a half rotation. On

120 the third reciprocation of finger 39 (the third after beginning with the parts positioned as shown in Fig. 7) the shaft 34 will be turned through a quarter turn, and then the rotation will be completed, and the sequence of turns now described will be re- 125 130

65 1. As weight 33 descends and approaches

peated. Thus the shaft 34 turns each time the skip moves away from the furnace top and in an ordered succession of turns of unequal amplitude: (1) a quarter turn, (2) a 5 half turn, (3) a quarter turn, (4) a quarter turn, (5) a half turn, (6) a quarter turn, and so on. That is to say, every third turn is a half rotation; the other two are quarter rotations.

- 10 A controlling device is provided for shaft 34 which, while allowing the shaft to turn as described in response to the downward thrust of finger 39, serves two ends: it holds the shaft positively and certainly to the precise degree of turning intended, and it prevents accidental and unintended turning—such, for instance, as might ensue in consequence of the contact, during the rise of finger 39, of the pins 41 and 42 against the 15 tangentially disposed rear faces of the teeth with which wheels 37 and 38 are provided. This controlling device in the form found adequate and here shown, consists of the essentially square block 42 (it may on its 20 corners be provided with friction rollers as shown) integrally carried on shaft 34, and the spring-backed block 43 bearing against the faces of block 42 as they are successively brought opposite to it. (The spring backing for block 43 is, for the sake of clearness of showing, omitted from Fig. 7, but the arrangement and action of this controlling device will be clearly understood on comparing Figs. 4, 5, and 10.)
- 25 The turning of shaft 34 in the ordered succession of unequal partial rotations effects the periodic descent of the distributing bell and the incidental discharge of the distributor, and it effects also (two times out 30 of three), and before the bell descends, the turning of the bell and with it the loaded distributor carried upon it, now 120° to the right, now 120° to the left. As has been said, in every third cycle of operation there 35 is no turning of the bell and sustained distributor.

I shall direct attention first to the vertical reciprocation of the distributing bell 16, and afterward to the rotation of the bell.

- 40 The distributing bell 16 is raised, as has been said, by the movement of the piston in cylinder 20; as the piston is driven down the bell ascends; and the bell is sustained in its elevated position, supporting the distributor, by the steam pressure above the piston in cylinder 20. The steam supply to drive the piston in cylinder 20 is from the 45 pipe 30, through pipe 44, to the valve chest 31, and thence by branch pipes to one end or the other of the cylinder. As has been 50 said, the valve in valve-chest 31 is a reversing valve; admitting, in its alternate positions, live steam to one end or the other of the cylinder 20 while opening the cylinder 55 at the opposite end to an exhaust. The

movement of the valve in valve chest 31 from one to the other of its alternate positions is effected by the motor 45, which conveniently takes the form of a steam cylinder supplied with steam from a common 70 source of power with cylinders 20 and 23. The control of this valve-driving motor is automatic.

Steam for operating motor 45 is conducted from pipe 30, through pipe 46, to valve-chest 47; from valve-chest 47 parallel steam lines 48 lead to valve chest 49; and from valve chest 49 two steam passages 50 communicate with opposite ends of the chamber within cylinder 45, and of course on opposite sides of the contained piston. The valve within valve chest 47 is movable from one to the other of two alternate positions indicated by the lines *a—a* and *b—b*; and in these positions it alternately opens communication from pipe 46 to one of the parallel pipes 48 and at the same time opens communication from the other pipe 48 to an exhaust 51. The valve in valve-chest 49 is a double-ported valve capable of being shifted from one to another of two alternate positions indicated by the lines *a—a* and *b—b*, and in these alternate positions it brings first one and then the other of pipes 48 into communication with one of passages 50 (and so with one end of cylinder 45) and brings the opposite end of cylinder 45 through the other passageway 50 into communication with the other one of the two pipes 48. From this it is apparent that the turning of either valve—the valve in valve-chest 47 or the valve in valve-chest 49—will reverse the steam supply to cylinder 45 and drive the contained piston from whichever end it be found to the opposite 105 end.

The valve in valve-chest 47 is shifted every time the descending distributing bell 16 comes to the end of its descent; the valve in valve-chest 49 is shifted every time the skip after spilling its load begins to descend the hoist.

First, of the valve in valve-chest 47 (cf. Figs. 4, 8 and 9). It is provided with a crank-arm 52, by which it is swung. Crank arm 52 is so linked to a crank-arm 53 on a shaft 54 that, with each complete rotation of shaft 54, the valve in chest 47 is shifted from one operative position to the other and then back again. Shaft 54 is rotated by a spur gear 55 which it bears, meshing with an internal gear on a disk 56, borne by a shaft 57. Shaft 57 is provided with a star-wheel 58, and a block 59 on a rod 60 reciprocates to turn the star-wheel. Star-wheel 58 is held by a dog 61 against retrograde movement. The result is that, when the rod 60 is lifted, the block 59, engaging one arm of wheel 58, turns shaft 57; but, when the rod is free and descends again, it 130

swings aside as block 59 passes the next arm of wheel 58, and comes to position with block 59 beneath the arm, ready for turning the wheel when the rod is raised again. A finger 62, borne conveniently by the cross-head to which the rod of the piston in cylinder 20 is connected (see Fig. 4), engages an adjustable stop on rod 60 and raises the rod as the cross-head comes to the end of its upward movement—that is to say, as the distributing bell comes to the end of its downward movement. When the piston in cylinder 20 moves downward rod 60 descends of its own weight. By making star-wheel 58 a four-armed wheel, so that shaft 57 turns a quarter of a rotation with each descent of the distributing bell, and by so proportioning the interior gear of disk 56 and the spur-gear 55 that the one has twice as many teeth as the other, the valve in chest 47 may be thrown from one position to the other with each descent of bell 16. Second, of the valve in valve-chest 49 (cf. Figs. 4, 5 and 6). It has been explained that shaft 34 turns whenever the skip, after spilling its load, starts on its descent down the hoist; it has been explained, further, that the turning of shaft 34 is, twice in three times, a quarter rotation and then a half rotation. A gear-wheel 63 is keyed to shaft 34; it meshes with a gear-wheel 64 on a shaft 65 (see Fig. 4). The gear wheel 63 is (Fig. 6) blank through one quarter of its periphery; the two gears are so proportioned that, while in mesh, shaft 65 makes a half turn while shaft 34 makes a quarter turn. Shaft 65 is provided with a controlling device (Figs. 6 and 11) similar to the controlling device already described as applied to shaft 34. It consists in this case of a block, not a four-faced block, but diametrically extending elongate block 66, with flat opposite faces, (the ends may, as indicated, have friction rollers), and of a spring-backed block 67. Block 67 bears against block 66; yields aside to allow shaft 65 to turn; and again engages the flat face of block 66 to hold the shaft 65 precisely and surely, against minor strains, to its alternate positions of half rotation. At the end of shaft 65 is a crank 68 (Fig. 4) which, turning through a half revolution with each rotation of the shaft, through suitable interconnecting rods and levers, generally indicated by the reference numerals 69, 70, throws the valve in valve-chest 49 from one to the other of its alternate positions. The parts are so assembled that, during the second half of the half rotation of shaft 34 (which, as has been explained, occurs once in three times), the blank portion of the periphery of gear 63 passes opposite gear 64; thus a regular succession of half turns is imparted to the shaft 65 from the irregular turning of shaft 34.

The shifting either of the valve in valve-chest 47 or of that in valve-chest 49 means the shifting of the motor element (the piston) in motor 45. The passages 50 are choked by adjustable needle valves; and, consequently, the reciprocation of the piston in the motor 45 is retarded; and a certain slow rate of moving is thus predetermined, for purposes presently to be described. The connection between the stem of the piston in motor 45 and the crank arm 71 by which the valve in valve-chest 31 is turned is telescopic (there is loose connection between the piston-stem and link 72—Fig. 12), so that it is only as the piston in motor 45 approaches the end of its reciprocation that the valve in valve-chest 31 is turned, first one way and then the other.

It will now be apparent that, when bell 16 descends, the valve in valve-chest 47 is reversed; in consequence, the piston in motor 45 makes its slow traverse from one end to the other (the particular direction is immaterial); and, when it comes to the end of its stroke, the valve in valve-chest 31 is reversed, and the steam supply in cylinder 20, up to that time entering at the bottom of the cylinder, is now reversed, and enters at the top. In consequence, bell 16 is raised, and continues in raised position sustaining distributor 4 upon itself, until a skip (having spilled a load into the distributor) begins to descend the hoist. Thereupon the valve in valve-chest 49 is reversed, and the piston in motor 45 again makes its slow traverse (again, the direction of movement is immaterial). As the piston in motor 45 approaches the end of its traverse, the valve in valve-chest 31 is reversed again, steam supply is cut off from above the piston in cylinder 20 and admitted below the piston. Bell 16 then descends, and the cycle of operations is repeated.

Meanwhile, after the skip-load has been dumped in the distributor and before the bell 16 descends, the distributor turning mechanism operates, and this remains to be described.

Shaft 34 is provided with a crank 73 and this turns with the shaft, (1) a quarter turn, (2) a half turn, (3) a quarter turn, (4) a quarter turn, (5) a half turn, and so on, every third turn being a half turn. This turning is imparted to the three-position valve in valve-chest 32, so that it takes the positions, (1) *a—a*, (2) *n—n—i. e. neutral*, (3) *b—b*, (4) *a—a*, (5) neutral, etc., so that with every movement of the skip from the furnace top the valve in valve-chest 32 is shifted, and the movement of the piston in cylinder 23 is correspondingly controlled. It is controlled to operate as follows: (1) up-stroke, (2) no movement, (3) down-stroke, (4) up-stroke, (5) no movement, (6) down-stroke, etc. The effect is that, in successive

operations, the distributor, after receiving the skip load, is correspondingly controlled, and turns (1) 120° to the right, (2) no turning, (3) 120° to left, (4) 120° to the right, 5 (5) no turning, etc. Now, since the skip spills always from the same point, the high point of the load, in consequence of this regulated turning of the distributor, is, as successive loads are discharged from the distributor, in regular succession brought to one after another of three points equally spaced around the periphery of the main bell. This makes for uniformity in distribution of the furnace charge.

10 15 The range of upward movement of bell 16 may be limited by adjustable stop screws 74.

It will suffice briefly to recapitulate the successive steps of automatic operation. A skip ascends the hoist and spills its load into 20 the distributor which, raised and sustained on bell 16, is waiting to receive it. The skip then begins its descent. Immediately weight 36 (which had been elevated as the skip approached the top of the hoist) falls 25 and shaft 34 is turned. Let it be assumed this turning is a quarter rotation. The valve in valve-chest 49 is by this turning reversed, and the piston in motor 45 begins its slow traverse. But the turning of shaft 30 34 has also effected the shifting of the valve in valve-chest 32. It will be assumed that this turning is from neutral to position $a-a$. Steam will thereupon be admitted to cylinder 23 to drive the contained piston 35 from the end at which it had previously stood to the opposite end. This traverse of the piston in cylinder 23 effects the turning of head 21, shaft 17, bell 16, and sustained distributor 5, through an angular swing of 40 120° —to the right, let us say.

This turning occurs while the slow-moving piston in motor 45 is completing its traverse. As it completes its stroke the 45 valve in valve-chest 21 is reversed; the supply of steam to cylinder 20 is reversed; and the loaded distributor, up to this point sustained by the steam pressure in cylinder 20, descends; the distributor rests on the rim of casing 4, and the further descent of bell 16 50 effects the discharge of the load.

As bell 16 comes to the limit of downward movement, rod 60 is raised, and the valve in valve-chest 47 is reversed. This effects the return of the piston in motor 45, the 55 shifting of reversing valve in valve-chest 31, the reversal of steam supply to cylinder 20, and the elevation again of bell 16. As the bell rises it picks up, raises, and sustains the distributor 5, ready for a new skip-load.

In the next operation shaft 34 turns 60 through a half revolution; motor 45 functions as before; but the valve in valve-chest 32 moves through a larger range, not merely 65 returning from position $a-a$ to neutral, but

passing neutral and coming to position $b-b$. The effect is that this time the distributor is turned 120° to the left.

In the third operation the shaft 34 turns through a quarter revolution, the valve in 70 valve-chest 32 comes to neutral position, and there is no turning of the distributor before its descent.

The next operation is like the first, and 75 operations succeed one another in the sequence described.

I have of necessity in the foregoing paragraphs described with care and with much detail the mechanism shown. Otherwise, I should not have been able to make plain all 80 of a somewhat complicated operation. It will however be understood that, in many respects, mechanical movements are shown to be accomplished by one of several available and well recognized means; and it will 85 further be understood that, in a larger way, the loads of material for charging the furnace may be handled according to my invention without employing the particular means which I have here set forth in an exemplary 90 way as preferred means. Accordingly, my claims which ensue are to be read and understood as defining types of mechanism of which the particular mechanism shown is but exemplary.

It will be understood that my invention is applicable not to blast furnaces merely, but generally to structures which include a chamber into which material is to be charged and within which an even or substantially even distribution of charged-in material is desired. I mean that the ensuing claims shall be understood to define my invention in such wider and more general applicability.

105 I claim as my invention:

1. In a blast furnace or like structure the combination with a chamber having a top opening, of a distributor having a bottom opening and vertically movable above said chamber to and from a seat in the chamber opening, a vertically moving bell arranged beneath said distributor and in the range of its movement alternately opening and closing the opening in the distributor and alternately raising and lowering the distributor from and to its seat, means for moving said bell vertically, and means for rotating said bell, at one time in one direction and at another time in opposite direction.

110 115 120 125 130 135 2. In a blast furnace or like structure, the combination of an open-topped chamber, a receptacle movable vertically from and to a seat in the open top of said chamber, a skip-hoist and a skip movable thereon to and from dumping position above said receptacle, means for bringing the skip on said hoist to dumping position above said receptacle, and means operating automatically and in correlation to said skip-moving means

for raising said receptacle from its seat before said skip comes to dumping position and lowering said receptacle to its seat again after said skip has come to dumping position.

3. In a blast furnace or other like structure, the combination of an open-topped chamber, a receptacle movable vertically from and to a seat in the open top of said chamber, a skip hoist and a skip traveling thereon to and from dumping position above said receptacle, means for bringing the skip on said hoist to dumping position above said receptacle, means operating automatically and in corelation to said skip-moving means for raising said receptacle from its seat before said skip comes to dumping position and lowering said receptacle to its seat again after said skip has come to dumping position, and further means operating automatically and in corelation to said skip-moving means and receptacle-moving means for rotating said receptacle after said skip has come to dumping position and before said receptacle descends.

4. In a blast furnace or like structure, the combination of an open-topped chamber, an open-bottomed receptacle movable vertically from and to a seat in the open top of said chamber, a vertically moving bell arranged beneath said receptacle, and in its range of movement closing the bottom of said receptacle and raising the receptacle from its seat in the top of the chamber, and again lowering the receptacle to its seat and opening the bottom of the seated receptacle, a skip-hoist and a skip movable thereon to and from dumping position above said receptacle, means for bringing the skip on the hoist to dumping position, and means operating automatically and in corelation to said skip-moving means for raising said bell and sustaining said receptacle above its seat before the skip comes to dumping position and for lowering said bell again bringing said receptacle to its seat and opening the bottom of said receptacle after said skip has come to dumping position.

5. In combination with a blast furnace or like structure of a rotary charging receptacle, means for periodically emptying said receptacle to said furnace, and means for rotating said receptacle during two out of three of the intervals between successive emptyings, such rotation being first in one direction and then in opposite direction.

6. In a blast furnace or like structure the combination with the structure itself of a charging receptacle arranged in its top opening and mounted for rotation, a skip-hoist and a skip rising and descending thereon and dumping successive loads into said receptacle, means operative periodically and in sequence after the dumping of a skip-load into it for emptying the recepta-

cle, and means for periodically rotating said receptacle two times out of three after it has received a skip-load and before it has been emptied, once in one direction and once in the opposite direction.

7. In a blast furnace or like structure having a top opening the combination with the structure itself of a bell centrally disposed with respect to that opening movable vertically and also rotary, a receptacle with a bottom opening alternately supported as the bell moves vertically on the rim of the bell and on the rim of the top opening in the structure itself, means for moving the bell vertically, and means for rotating the bell first in one direction and then in opposite direction.

8. In a blast furnace or like structure having an open top, the combination, with the structure itself, of a bell vertically movable adjacent the opening in the top of the structure, an open-bottomed receptacle resting alternately, as said bell moves up and down, on the bell itself and on the rim of the opening in the top of the structure, a steam cylinder to the piston of which said bell is operatively connected, a steam supply line leading through branches to opposite ends of said cylinder, a reversing valve which in alternate positions directs steam to one side and the other of said cylinder, a skip movable to and from dumping position above said receptacle, means for shifting said valve in one direction in response to movement of said skip, and means for moving said valve in opposite direction in response to vertical movement of said bell.

9. In a blast furnace or like structure having an open top, the combination, with the structure itself, of a bell vertically movable and also rotary on a vertical axis adjacent the opening in the top of said structure, an open-bottomed receptacle resting alternately, as said bell moves up and down, on the bell itself and on the rim of the opening in the top of the structure, a motor for moving said bell vertically, a reversing device for said motor, a skip movable to and from dumping position above said receptacle, means operated by movement of said skip for moving said reversing device in one direction, means operated by the movement of the bell for moving said reversing device in opposite direction, and means for rotating said bell.

10. In a blast furnace or like structure having an open top, the combination, with the structure itself, of a bell vertically movable and rotatable on a vertical axis adjacent the opening in the top of the structure, a receptacle having an open bottom and resting, as said bell moves up and down, alternately on the bell and on the rim of the opening in the top of the structure, a skip movable to and from dumping position

above said receptacle, a steam supply line, a cylinder containing a piston driven in opposite directions by steam from such supply and operatively connected to said bell, a reversing valve in the line of steam supply to said cylinder, a second cylinder containing a piston driven in opposite directions by steam, a suitable steam supply for said second cylinder, loose connection between the piston in said second cylinder and said reversing valve, separate means operated the one by movement of said skip and the other by the movement of said bell for reversing the steam supply to said second cylinder, means for retarding the movement of the piston in said second cylinder, and means operated by the movement of said skip for turning said bell.

11. In a blast furnace or like structure having an open top, the combination, with the structure itself, of a bell vertically movable and rotatable on a vertical axis adjacent the opening in the top of the structure, a receptacle having an open bottom and resting, as said bell moves up and down, alternately on said bell and on the rim of

the opening in the top of the structure, a skip movable to and from dumping position above said receptacle, a motor for moving said bell vertically, a reversing device for said motor, a steam cylinder, a steam supply for said cylinder, loose connection between the piston in said cylinder and said reversing device, provision for retarding the traverse of the piston in said cylinder, a shaft, mechanical connection between said skip and said shaft, whereby said shaft is turned as said skip moves from dumping position, means operated by the turning of said shaft for reversing the steam supply to said cylinder, means operated by the turning of said shaft for turning said bell, and means operated by the vertical movement of said bell for reversing again the steam supply to said cylinder.

In testimony whereof I have hereunto set my hand.

GEORGE L. COLLORD.
